PROCESS FOR PLUGGING BACK OR BRIDGING WELLS

Filed April 10, 1934

UNITED STATES PATENT OFFICE

2,014,563

PROCESS FOR PLUGGING BACK OR
BRIDGING WELLSErle P. Halliburton, Los Angeles, Calif., assignor
to Halliburton Oil Well Cementing Company,
Duncan, Okla., a corporation of Delaware

Application April 10, 1934, Serial No. 719,883

6 Claims. (Cl. 166—21)

This invention relates to a process and apparatus for plugging back or bridging wells, such as oil wells, by cement.

When a well, such as an oil well, has been drilled beyond an oil producing formation into a water sand therebelow, it is sometimes desirable to plug up the bottom of the oil well. This operation is termed the plugging back operation. There are various other reasons which may make it desirable to plug a well-hole at some desired point to shut off the formations below from the formations above.

Heretofore, when an oil driller has attempted to plug off or bridge the bottom of a well-hole, the operation has been accompanied by danger of sticking a pipe in the well-hole. The general practice has been to insert into the well a casing or tubing leading to near the bottom of the well. The fluid cement is then pumped through the tubing or casing to a height somewhat above the point where the well is to be shut off or plugged, and the casing has then been elevated to the desired shut-off point, whereupon the excess cement has been removed from the well-hole by circulating mud down the casing or tubing to wash out such excess cement. Quite frequently, it is found that the casing or tubing has been frozen at the bottom of the well-hole by the cement when it is desired to elevate the same.

It is the general object of the present invention to provide a process and apparatus which may be used for plugging back or bridging oil wells without danger of freezing the casing or tubing in the well-hole.

It is a further object of the present invention to provide a process and apparatus for plugging back or bridging oil wells, which is more easily performed and more certain in operation than the process and apparatus heretofore used.

In general, the process and apparatus of the present invention comprehends that the danger of freezing the tubing in the well may be avoided by the provision at the end of the tubing of a special "plug back" device or section of tubing detachable from the remainder of the tubing, so that it may be intentionally left in the bottom of the well-hole after the plugging back or bridging operations. By constructing such "plug back" device or section of tubing of such material that it may be readily drilled from the well-hole, the plugging back operation will not interfere with future deepening of the well-hole, in case such operations are later found desirable.

The present invention further comprehends

that the process of plugging back the oil well may be more readily and certainly accomplished if in the process and apparatus provision is made for circulation of mud fluid at the desired shut-off point without disconnecting the tubing from the lower section or "plug back" device, and for this purpose the present process and apparatus makes special provision for such circulation.

A further feature of the present process and apparatus is the use of plugs, and cooperating apparatus for catching or arresting the plugs at desired points by which the position to which the cement is forced in the operations is automatically determined so that it becomes unnecessary to judge when the cement is in the desired position by measuring the amount of fluid introduced into the well-hole. In the usual practice of plugging back or bridging a well-hole, the operator has to measure the amount of fluid introduced in the well-hole in order to estimate when the cement has been passed to the desired point. This measuring operation is accompanied by frequent errors, and as a result the well is frequently bridged or shut off at the wrong point.

Various further advantages and features of the present invention will be apparent from a description of a preferred form or example of a process and apparatus embodying the invention. For this purpose, one form or example of such a process and apparatus is hereafter described with reference to the accompanying drawing, in which,—

Figure 1 is a sectional view of an oil well with an apparatus installed therein illustrating the position of the apparatus and the stage of the process during the operation of pumping the cement into the well-hole;

Figure 2 is a similar view of the apparatus showing the position at the stage of the process after the cement has reached the desired position and the apparatus is in position for washing out the excess cement;

Figure 3 is an enlarged vertical section of the "plug back" device; and

Figure 4 is an enlarged vertical section of the releasing device and slide valve member, preferably included in the process and apparatus.

Referring to the drawing, the apparatus comprises a string of pipe or casing 1, which may be built of sections in any usual or preferred manner. The lower end of the string of pipe 1 is attached to a releasing device and slide valve member 2. The releasing device and slide valve mem-

ber 2, in turn, is detachably connected with the "plug back" device 3.

Now, referring more particularly to Fig. 3, the "plug back" device 3 may be any form of tubing 5 provided with a suitable means, such as a J-slot 4, for readily detaching the same from the releasing member 2. In place, for example, of the J-slot connection, such as indicated at 4, other suitable connection means, such as a left-hand 10 thread, may be employed. The "plug back" device is shown as including a back pressure valve 5 at near its upper end and with the distributing nozzle 6^a at its lower end. The "plug back" device should be constructed of a material or materials 15 which can be readily drilled out of the bottom of the well-hole, if later it should be desired to again drill out the bottom of the well-hole.

The preferred form of the "plug back" device illustrated comprises the upper collar 6, which 20 contains the J-slot 4 and is provided with a seat 7 for the back-pressure valve 5. This collar, in turn, is threaded to a nipple 8, which is indicated as having a reduced portion 9, which in its lower end connects with a thin sleeve 10. The lower end of the sleeve 10 connects with a nipple 11 similar to the nipple 8, which in turn, is threaded to the nozzle 6, which is preferably provided with a lower discharge port 12 and a plurality of equally spaced apart lateral discharge ports 13.

30 Between the nipples 11 and 8 is the body of the "plug back" device, which may in practice be of various lengths, depending upon the distance that the oil well is to be plugged back in operation. In order to construct the device so that 35 it may be most easily drilled out of the well-hole, a body of the device between the nipples 8 and 11 is formed of hardened cement or concrete 14, which may be suitably strengthened by a reinforcing screen 15, if desired. The other portions 40 of the "plug back" device, such as the collar 6, nipples 8 and 11, and distributing nozzle 6^a should be formed of a material easy to drill, such as aluminum or easily fractured cast iron.

The releasing and slide valve member 2 (Fig. 4) comprises a tube 16, preferably provided near its lower end with a cross-pin 17 adapted to enter J-slot 4 of the "plug back" device 3 for attaching such "plug back" device to the tubing 1. The upper end of the releasing device 2 is provided 50 with a threaded socket 18 or other suitable means for attaching the same to the body of tubing 1. The process and apparatus may, if desired, rely upon detaching the "plug back" device from the tubing for the operation of washing out the excess cement, but preferably this releasing member 55 2 is made to include a slide valve. For this purpose, the tube 16 is provided with one or more lateral ports 19 normally closed by a sleeve 20 telescoped within tubing 16. This sleeve 20 60 at its lower end rests upon pins 21 which are constructed of a material readily sheared, so that in operation by shearing the pins 21 the sleeve 20 may be lowered to operate as a valve and uncover the ports or port 19. The sleeve 20 is preferably 65 provided near its lower end with a restricted member 22 for the purpose of catching and holding plugs in the manner hereafter described.

The apparatus also preferably includes a lower 70 plug 23 (Fig. 1) and an upper plug 24. The lower plug 23 may be composed of a material, such as rubber, and is provided with a diaphragm 25 which under pressure is adapted to blow out for the purposes hereinafter described. The upper plug 24 may be any usual customary form of 75 plug for cementing purposes.

The process of plugging back or bridging wells in accordance with the present invention as carried out with the use of such apparatus is as follows:

The tubing 1 is attached to the releasing member 2 which, in turn, is attached to the "plug back" device 3, and the assembled apparatus then lowered into a well-hole, such as indicated at 26, until the top of the "plug back" device 3 is at substantially the point at which it is desired 10 to bridge or plug back the well-hole. Circulating fluid, such as mud, is then introduced into the apparatus, as indicated at 27, and circulated down the apparatus to return up and around the apparatus to the top of the well-hole in order to 15 insure that the bottom of the well-hole is free. There is then introduced the plug 23, the purpose of which is to keep the cement separated from the circulating fluid until this cement has been pumped down into the well-hole. After the introduction of the plug 23, fresh fluid and unset cement is introduced into the apparatus above the plug 23 in sufficient quantities to fill the bottom of the well-hole up to the desired bridging or plugging off point. In practical operation, it 25 is found always necessary to introduce an excess amount of cement, as the exact requirements for plugging off the bottom of the well cannot be determined. When the desired amount of cement 30 28 has been introduced, there is then inserted the upper plug 24, the purpose of which is to protect the cement from contamination with the fluid later to be inserted above the plug 24. Circulating fluid, such as mud, is then introduced into the apparatus, as indicated at 29, 35 by means of a pump and by continued pumping the cement is forced down the apparatus.

The plug 23 descends until it encounters the restriction member 22. It is held from further descent by this member and the force of the 40 pump introducing the circulating fluid 29 is sufficient to burst the diaphragm 25 of this plug and the cement 28 then passes downwardly through the "plug back" device out of the distributing nozzle 6^a and rises again around the 45 apparatus. The upper plug 24, in turn, descends until it strikes the lower plug 23, after which the continued pump pressure causes the pins 21 to shear which are holding the sleeve valve 20 closed. The sleeve valve 20 then descends until it strikes the pin 17, opening the slide valve ports 19. This checks the descent of the cement, which then remains in the apparatus from the pin 17 through the "plug back" device and up around the "plug back" device to a 55 height somewhat above the ports 19. By further pumping down the tubing 1, the circulating fluid or mud is caused to pass out of the ports 19 and rise up around the tubing 1, carrying to the surface of the well the excess cement. In 60 certain cases, it may be desirable at this point to reverse the circulation forcing fluid mud down the outside of the pipe 1 and cause the excess cement to be forced up inside of the pipe. After the excess cement has been removed from the 65 well-hole, the "plug back" device is detached from the tubing 1 by lowering and turning tubing 1 to disengage the pin 17 from the J-slot 4. Leaving the "plug back" device in the well-hole, the remainder of the apparatus is then withdrawn to the top of the well. The back-pressure valve 5 operates to prevent the cement at the bottom of the well-hole from flowing out of the "plug back" device.

While the particular form of the process and 75

apparatus herein described is well adapted to carry out the objects of the present invention, various modifications and changes may be made without departing from the principles of the invention, and this invention includes all such modifications and changes as come within the scope of the appended claims.

I claim:

1. A process of plugging a well, which comprises lowering a string of pipe into a well-hole until its lower end is below the point at which the well hole is to be plugged off, forcing unset cement down the string of pipe in sufficient quantity to more than occupy the space in the well-hole to the plug-off point, circulating fluid down the pipe and into the well-hole above the plug-off point to remove the excess cement, detaching that portion of the pipe below the plug-off point, and removing the remaining pipe from the well-hole.

2. A process of plugging a well, comprising lowering a string of pipe into the well-hole, having at its lower end a detachable section composed of drillable material, the pipe being lowered to bring the detaching point at the height at which the well is to be plugged off, forcing cement down the string of pipe in sufficient quantities to fill the well-hole to above the detaching point, circulating fluid above the detaching point to remove the excess cement, detaching the lower section of the pipe, and removing the remaining pipe from the well-hole.

3. A process of plugging a well, comprising lowering a string of pipe into a well, with a detachable lower section composed of drillable material and a slide valve thereabove, the pipe being lowered to bring the detachable lower section at the point where the well is to be plugged off, introducing cement into the well-hole of the pipe until cement rises outside of the pipe to above the point where the well is to be plugged off, opening the valve and then circulating fluid through such valve to remove the excess cement, detaching the detachable lower section of the

pipe, and removing the remaining pipe from the well-hole.

4. A process of plugging off a well-hole, comprising lowering into the well-hole a string of pipe having a detachable lower section composed of readily drillable material and having thereabove a plug actuated slide valve, introducing cement into the well-hole through the string of pipe, inserting the plug in the pipe above the cement and pumping cement downwardly by the use of circulating the fluid introduced above the plug until the plug is caused to operate in the side valve, then continuing the pump operations to cause a circulation of the circulating fluid to remove any excess cement introduced into the well-hole.

5. A process of plugging a well-hole, comprising lowering a string of pipe into the well-hole, with a detachable lower section composed of drillable material, then establishing circulation in the well-hole through the string of pipe, inserting in the pipe a plug having a blow-out diaphragm, introducing into the pipe above said plug sufficient fluid cement for plugging off the well to the desired height, inserting a second plug above said cement, and then forcing into the pipe drilling fluid to force said cement down the well-hole, then circulating fluid to remove excess cement, detaching the lower section of pipe, and removing the remaining pipe from the well-hole.

6. A process of plugging a well-hole, which process comprises lowering the string of pipe into a well-hole, having a detachable lower section equipped with a back-pressure valve, introducing cement into the well-hole through the string of pipe until the same occupies a space within and outside of the detachable lower section of pipe, circulating fluid above such detachable section to remove excess cement, disconnecting the remaining pipe from the detachable section, and removing the same from the well-hole.

ERLE P. HALLIBURTON.
